HENRY L. SMITH, OF WATERBURY, CONNECTICUT, ASSIGNOR TO THE E. J. MANVILLE MACHINE COMPANY, OF WATERBURY, CONNECTICUT, A CORPORATION OF CONNECTICUT.

BLANK-FEEDING MECHANISM.

1,262,117.

Specification of Letters Patent. Patented Apr. 9, 1918.

Application filed October 3, 1917. Serial No. 194,465.

To all whom it may concern:

Be it known that I, HENRY L. SMITH, a citizen of the United States, residing at Waterbury, in the county of New Haven 5 and State of Connecticut, have invented a new and useful Improvement in Blank-Feeding Mechanism, of which the following is a specification.

This invention relates to those mechanisms for feeding metal blanks of the type 10 illustrated in U. S. patent to Charles T. Brennan No. 1,180,903, April 25, 1916, which mechanisms pick headed blanks from masses in hoppers and feed them to the operating 15 tools of such machines as bolt and screw headers, trimmers, pointers, threaders, slotters and rollers. Mechanisms of this class have in the hoppers oscillatory elevators which move down into the promiscuous mass 20 of blanks and carry up blanks to the ends of inclined tracks down which those blanks that are properly presented slide hanging by their heads. Frequently the blanks are lifted crosswise or in other positions so 25 that they obstruct the tracks and thus interrupt the feed of the blanks to the operating tools. To obviate this monitors, such for instance as the reciprocatory comb of the machine of the patent referred to, have 30 been arranged at the upper ends of the tracks to knock off the misplaced blanks and permit the free flow down the tracks of those blanks which are correctly presented. In 35 practice it has been found, particularly when feeding long blanks, that the tracks would load up at the ends in the hoppers, that is, blanks would accumulate therein and when the elevators rose these blanks would be pushed up and the monitors would become 40 broken and rendered inoperative.

The object of this invention is to provide a very simple means for a feeding mechanism of the class mentioned, which will as the elevator descends cause the blanks that 45 have accumulated improperly between the plates at the end of the track to be precipitated back into the hopper and thus leave the end of the track free for receiving such blanks as are brought up by the elevator in 50 proper position to pass the monitor and slide down the track, and eliminate the possibility of so lifting the blanks as to injure the monitor.

The track is formed of two plates spaced 55 apart so that the shanks of the blanks will

hang substantially vertical when their heads rest upon and slide down the upper inclined edges of the plates. It is the space between the upper ends of these track plates that tends to load up with an accumulation of 60 blanks and put the monitor, which is on top at the ends of the track plates, out of commission, and to attain the object of this invention a diverting plate is arranged in the space between the ends of the track 65 plates in such manner as to cause the blanks that accumulate therein to be thrown back into the hopper when the elevator descends.

Figure 1 of the accompanying drawings shows a side view of a blank feeding mechanism which embodies this invention. Fig. 2 shows a plan of the same. Fig. 3 shows a vertical section through the hopper on the plane indicated by the dotted line 3—3 on Fig. 2. Fig. 4 is a side view on larger scale 70 of the end of the track and of the monitor, illustrating the manner in which the misplaced blanks accumulate wrongly in the track and are thrown back into the hopper when the elevator descends. Fig. 5 is an 75 edge view of the parts shown in Fig. 4.

The hopper 1 is a cast iron receptacle of common shape. Movable up and down in this hopper is the elevator 2 which is formed of two segmental plates spaced apart a distance substantially equal to the diameter of the shanks of the blanks to be elevated. This elevator is secured to an arm 3 fastened on an arbor 4 mounted in a bracket 5 attached to the outside of the hopper. On the 80 other end of the arbor is a rocker arm 6. A link 7 connects the rocker arm with a crank 8 on the shaft 9 bearing the gear wheel 10. This gear is engaged by a pinion 11 on the shaft 12 bearing the driving pulley 13. By 85 means of this mechanism the elevator is oscillated up and down in the hopper at the desired intervals.

Extending through an opening in the front wall of the hopper in the usual manner 100 is the track formed by the two plates 14 which are arranged some distance apart with their upper edges on an incline. The blanks that are raised properly, that is, by their heads with their shanks hanging down 105 between the elevator plates, when the elevator is in its uppermost position slide down the elevator and down the track as do the blanks 15 in Fig. 4.

In case any of the blanks are brought up 110

by the elevator crosswise or are misplaced in any other way, to prevent them from accumulating in the hopper on top of the track and forming an obstruction, a comb 16 is arranged to be reciprocated on the inclined edge of the track at its upper end. This comb has an opening which permits the passage of the heads of the bolts that are in proper position to slide down the track, 10 but not allow the passage of misplaced blanks. The comb is fastened to an arm 17 which outside of the hopper is connected with a slotted link 18 that is pivotally hung on a bracket 19. Extending into the slot 15 in the link is a crank pin 20 projecting from a crank disk 21 on the end of a shaft 22, mounted in the bracket. This shaft is provided with a pulley 23 and this pulley is connected by a belt 24 with a pulley 25 on 20 the driving shaft 12. By means of this mechanism the comb is given a desired reciprocation, and acts as a monitor which permits the feed of properly raised blanks and knocks off into the hopper such blanks 25 as are not properly presented for feeding.

The blanks sometimes accumulate wrongly in the space between the ends of the track plates, as illustrated by the blanks 27 in Fig. 4. Should the blanks remain in this 30 space in this position and the elevator come up with a load of blanks, the blanks improperly accumulated between the track plates would be forced up in such manner as to break the comb and render it inoperative. To obviate this a plate 28 with an 35 inclined upper edge is fastened to the inside one of the track plates. This plate has its outer edge shaped to fit between the edges

of the elevator plates. With this simple arrangement when the elevator goes down 40 such blanks as have improperly accumulated between the track plates are precipitated out from between the track plates and fall by gravity back into the hopper, as are the 45 blanks 29 in Fig. 4, so that when the elevator rises there is no accumulation of improperly placed blanks that can be forced up to break the comb.

The invention claimed is:

1. In an automatic blank feed the combination with a hopper and an inclined track leading therefrom, of an elevator adapted to be lowered and raised in the hopper, mechanism for raising and lowering the elevator, a monitor movable on the inclined edge of the track near the upper end, mechanism for actuating the monitor, and a diverting plate arranged between the ends of the track plates for causing misplaced blanks to be precipitated from between the 50 track plates into the hopper when the elevator descends.

2. In an automatic blank feed the combination with a hopper and an inclined track leading therefrom, of an elevator adapted to be raised and lowered in the hopper, mechanism for raising and lowering the elevator, a monitor adapted to be moved along the edge near the upper end of the track, mechanism for actuating the monitor, and a 55 plate with an inclined upper edge attached between the ends of the track plates for causing misplaced blanks to be precipitated from between the track plates into the hopper when the elevator descends.

HENRY L. SMITH.
